APPARATUS FOR WASHING CLOTHES AND CENTRIFUGALLY EXTRACTING LIQUID THEREFROM

Tord Erik Daniel Bilde and Rolf Bertil Johannes
Hultberg, Stockholm, Sweden, assignors to
Aktiebolaget Electrolux, Stockholm, Sweden,
a corporation of Sweden

Application June 25, 1947, Serial No. 756,890
In Sweden February 23, 1945

5 Claims. (CL. 68—26)

1

Our invention relates to clothes washing apparatus, and more particularly to such apparatus for washing clothes and other fabrics and the like and centrifugally extracting liquid therefrom.

An object of our invention is to provide an improved washing and liquid extracting apparatus of simplified construction which can be readily assembled.

Another object of our invention is to provide an improved apparatus of this kind in which the different parts are readily accessible, the washing and liquid extracting units being constructed in such manner that individual parts can be conveniently removed for cleaning and inspection while disturbing only a minimum number of other parts of the apparatus.

A further object of our invention is to provide an improved apparatus in which the washing and liquid extracting portions are constructed as separate units independently mounted alongside each other on a common base in such manner that maximum protection from washing liquid is afforded for the driving motor and mechanism operatively associating such motor and parts of the washing and liquid extracting units.

A still further object of our invention is to provide an improved apparatus of this kind in which the driving motor is housed within the liquid extracting unit and related to other parts in such manner that it is nicely protected and may be readily removed for inspection and cleaning.

Further objects and advantages of our invention will become apparent as the following description proceeds, and the features of novelty which characterize our invention will be pointed out with particularity in the claims annexed to and forming a part of this specification.

In the drawing, Fig. 1 is a vertical view taken at line I—I of Fig. 2, partly in section and partly in elevation, illustrating a combined washing and liquid extracting apparatus embodying the invention; and

Fig. 2 is a top plan view looking down on the apparatus shown in Fig. 1.

In the drawing, we have shown our invention embodied in a combined washing and liquid extracting apparatus comprising a base 9 upon which are separately mounted a washing unit 10 and a liquid extracting unit 11. A suitable source of heat, such as, for example, a gas burner 12, is associated with the washing unit 10. A driving motor 14 for the apparatus is located within the lower part of the liquid extracting unit 11.

Suitable mechanism is provided whereby the motor 14 may be employed to drive a rotatably mounted perforated drum or basket 15 within the liquid extracting unit 11 for centrifugally extracting washing liquid from the clothes, and also for

2

oscillating a washing element or agitator 16 within a washing receptacle 17 forming a part of the washing unit 10. The mechanism operatively connecting the motor 14 to the drum 15 and to the washing element 16, as well as the motor itself, is protected from washing liquid collecting in the liquid extracting unit 11 and liquid which may be splashed when the apparatus is in use.

The various parts of the apparatus briefly referred to, and which will be described more fully hereinafter, are associated with one another in such a way that each part is readily accessible and can be conveniently removed for cleaning and making repairs while disturbing only a minimum number of other parts of the apparatus.

The washing unit 10 comprises the washing receptacle 17 of cylindrical form having a bottom 18 and an upstanding side wall including a short bottom wall portion 19 of reduced diameter, and a higher extending main wall portion 20 of wider diameter. The upper end of the upstanding side wall is formed with an inwardly extending flange 21 shaped to receive and hold a cover (not shown) to prevent spilling of washing liquid. The agitator 16 is mounted in the receptacle 17 for oscillation therein about a horizontally extending axis and may be of a type like that described in application Serial No. 542,865 of T. E. D. Bilde, filed June 30, 1944, now Patent No. 2,491,081, granted December 13, 1949. It is to be understood, however, that the particular agitator or washing element referred to is merely illustrative and that other types of washing elements may be employed.

The agitator 16 is suitably journalled at one end in a bearing 22 fixed to the inside of the receptacle 17, and at its opposite end may be removably connected in any well known manner to a driven member 23 extending through an opening 24 in the receptacle. The member 23 is associated with and forms a part of mechanism 25 mounted on the outside of the receptacle 17 which may be of any conventional type operable to oscillate the agitator 16 back and forth within the receptacle.

The main wall portion 20 of the upstanding side wall at its lower part flares outwardly from the short wall portion 19 which essentially forms a neck of reduced diameter at the bottom of the receptacle. A perforated plate 26 is positioned in the receptacle 17 at the region from which the main wall portion 20 flares outwardly from the reduced neck portion 19. The perforated plate 26 serves as the actual bottom for the space in which the clothes to be washed are circulated and is formed with a downwardly extending flange 27 which snugly fits within the reduced neck portion 19 of the receptacle. While the clothes are held in the space above the plate 26, the washing liquid can circulate between the spaces above and

below such plate through the apertures 28 therein.

The washing receptacle 17 is mounted on a stand comprising a housing 29 of cylindrical shape which may be formed of sheet metal. The upper end of the housing 29 receives the neck portion 19 of the receptacle, and these parts are tightly secured together by a metal band or split ring 30 having ears or tabs 31, only one of which is shown, adapted to be drawn toward each other by a tightening screw 32. The neck portion 19, the upper end of the housing 29, and the ring 30 are formed with similar-shaped annular ridges so that these parts can be brought together with the ridges in nested relation, as shown in Fig. 1. In addition, the upper edge portion of the housing 29 may be slotted at spaced apart regions so that it will be sufficiently resilient to enable the ring 30 to draw the housing tightly about the reduced neck portion 19 of the washing receptacle 17.

Within the housing 29 is provided a horizontal partition 33 having a central opening about the peripheral edge portion of which is fixed the lower end of a tube or sleeve 34. The gas burner 12 is supported on the partition 33 by a number of brackets 35, only one of which is shown, and so positioned that the burner flames project upwardly through the sleeve 34 to effect heating of the bottom 18 of the washing receptacle 17. Gas is supplied to the burner 12 through a conduit 36 which passes through an opening in the housing 29 and is provided with a manually operable valve 37 and a nipple connection 38 to which a flexible gas line (not shown) is adapted to be connected for delivering gas from a suitable source of supply.

Combustion supporting air for the burner 12 enters the housing 29 through the lower open end of the washing unit 10, and the heated products of combustion pass from the heating chamber 39 through an opening 40 in the housing 29 to which an exhaust flue 41 may be connected. The washing unit 10 may also be arranged for electrical heating, if desired, in which case one or more electrical heating elements may be provided in the space between the bottom 18 of the receptacle and the apertured plate 26.

The liquid extracting unit 11 comprises an outer shell or casing 42 of cylindrical form whose height is substantially the same as the overall height of the housing 29 and the washing receptacle 17 of the washing unit 10. Within the upper part of the casing 42 is disposed the perforated drum 15 which is adapted to be rotated for extracting washing liquid centrifugally from the clothes. The upper open end of the basket 15 receives a freely rotatable disc 43 journaled at 44 in a cover 45 which is hinged at 46 and adapted to be clamped in any suitable manner (not shown) in a closed position. When the cover 45 is locked in its closed position and the basket 15 is being rotated, the disc 43 will also rotate and serves to guide the basket 15 at its upper end and prevent wobbling movement thereof when the basket is being driven at a relatively high speed.

An imperforate plate 47 is provided at a region within the drum 15 which is spaced from the extreme lower imperforate end thereof and defines the bottom of the space for holding the clothes from which washing liquid is extracted. To the extreme lower end portion of the drum 15 is fixed a bottom end member 48 having a centrally disposed opening within which is rigidly connected the upper tapered end of a shaft 49. The shaft 49 is arranged in a ball bearing 50

secured in an annular member 51 whose outer peripheral edge portion is fixed to the inside of the shell 42, as by welding or brazing, for example. Suitable packing 52 is preferably provided above the bearing 50 to protect the latter from moisture.

The annular member 51 is formed with a V-shaped trough 53 in which liquid collects and from which the extracted liquid flows by gravity into a suitable collecting vessel (not shown) through an inclined discharge spout 54 extending through an opening in the shell 42.

The washing unit 10 and liquid extracting unit 11 just described are separately mounted on the base 8 which is suitably formed of sheet metal and includes a top plate 55 and a vertical side wall 56 having an inwardly extending reinforcing flange 57 at its lower end. Hence, the base 8 is completely open at the bottom at the region of the flange 57.

The top plate 55 is provided with two circular openings at the peripheral edges of which are removably secured the lower ends of the housing 29 and shell 42, respectively. As shown, the lower ends of the housing 29 and shell 42 fit over collars or rings 58 and 59, respectively, and rest on the upper face of the top plate 55 at the peripheral edges of the openings. The collars 58 and 59 fit snugly in the openings and are formed with inwardly extending upper flanges 60 and 61 and outwardly extending lower flanges 62 and 63, the lower flanges being adapted to bear against the underside or face of the top plate 55.

The collars 58 and 59 and the lower ends of the housing 29 and shell 42, respectively, are formed with a number of aligned openings through which pass threaded bolts 64 adapted to receive tightening nuts 65. Strips of metal 66, which are curved or arched in section, are disposed about the lower ends of the housing and shell to hide the heads of the bolts 64 from view and provide a neat appearance at the base 8.

The base 8 is provided with three or more legs 67 which are fixed thereto in any suitable manner for supporting the apparatus in a slightly elevated position on a supporting surface 68. The legs 67 may be arranged to receive casters (not shown) to facilitate movement of the apparatus, and may also be of a type which are adjustable to make it possible to raise and lower the washing unit 10 and liquid extracting unit 11 when this is desired.

It will now be seen that the two units 10 and 11 are separate and distinct and are independent of one another. Due to the manner in which the units 10 and 11 are removably secured to the base 8, each unit may be removed from the base independently of the other. Moreover, since the units 10 and 11 are in spaced relation, a gap is provided between the units which is completely open. This gap at the top of the units 10 and 11 is bridged by a suitable table plate 69 which desirably is relatively thick in section and may extend from the washing receptacle 17 to the extreme outer or remote end of the liquid extracting unit 11, as shown most clearly in Fig. 2. The part of the table plate 69 extending beyond the gap between the units 10 and 11 and overlying the shell 42 is formed with an opening through which access is had into the shell 42 and drum 15 therein. The cover 45 for the liquid extracting unit may be hinged at 46 to the table plate 69.

The table plate 69 is formed with a downwardly extending sleeve portion 70 which is re-

ceived by the upper end of the casing 42, and also a leg 71 of such shape that it bears snugly against the outer surface of the washing receptacle 17. The table plate 69 is removably secured in position in any suitable manner, as by countersunk caps screws (not shown), for example; and is formed with a slightly raised rim 72 and an inclined ramp 73 so that washing liquid that collects on the table plate during a washing operation, as during the transfer of clothes from the washing receptacle to the drum 15, will flow by gravity into the washing receptacle.

The compartment 14 provided in the bottom part of the casing 42 is advantageously employed to house the electric motor 14 arranged to rotate the drum 15 and actuate the washing element 16. As previously described, the annular member 51 and bearing 50, together with its associated packing 52, are of such construction that extracted liquid is prevented from passing 10 into the compartment 14 and all of the liquid collecting at the top surface of annular member 51 flows through the discharge spout 54.

The motor 14 having shaft 75 is removably mounted at 76 to the inwardly extending flange 61 of the collar or ring 59. Several mounts 76 may be provided which are distributed about the flange 61 and preferably resilient in character to dampen vibrations of the motor and minimize the transfer of such vibrations to the 15 casing 42 and base 9 of the apparatus.

The shaft 75 of the motor 14 is in alignment with the shaft 49 rigidly fixed to the lower end of the rotatable drum 15 and arranged to drive the latter through a friction clutch comprising 20 cooperating elements 77 and 78. The lower element 77 is rigidly fixed to the upper end of the motor shaft 75, while the upper element 78 and a collar 79 fixed thereto are keyed on the shaft 49 and only axially movable thereon. The collar 79 and upper element 78 may be shifted up and down on the shaft 49 in any suitable manner. For example, the collar 79 may be arranged to receive the end of an operating member or lever 80 which may be operatively connected to a 25 manually operable control conveniently located on the apparatus.

While the clutch just referred to may be of any suitable type, we have shown a friction clutch like that described in application Serial No. 761,300, of R. B. J. Hultberg, filed July 16, 1947. In such a friction clutch the upper element 78 is in the form of a brush which, when it is moved downwardly, is adapted to engage the top face of the lower element 77. The frictional engagement of the ends of the brush bristles and the top face of the lower element are effective to transmit turning movement to the shaft 49 and drum 15 rigidly fixed thereto. With a friction clutch of this type, the motor 14 may be operated at its normal full speed and, due to the sliding frictional engagement of the brush bristles on the lower element 77 when the elements are brought together, the drum 15 will gradually increase in speed until it reaches the normal speed of the driving motor.

As previously mentioned, the motor 14 is also arranged to actuate the washing element or agitator 16. The mechanism 25 mounted on the outside of the washing receptacle 17 is of a type which is operable to impart an oscillatory movement to the agitator 16. The mechanism 25 is completely enclosed within a shell designed to close the opening 24 in the side wall of the receptacle, and suitable provision is made to prevent 70

washing liquid splashing from the receptacle past the driven member 23 into the shell of the mechanism.

5 A shaft 81 extends vertically downward from the mechanism 25 in the gap between the washing unit 10 and liquid extracting unit 11, and is journaled at its lower end within a sleeve member 82 at the underside of the top plate 55 of the base 9. In order to protect the shaft 81 from washing liquid, the latter is preferably housed in a hollow tube 83 connected at its upper end to the shell of the mechanism 25 and at its lower end to the top plate 55. The shaft 81 is adapted to be driven continually in one direction, and the mechanism 25 operatively connected thereto converts such continuous turning movement of the shaft 81 into an oscillatory movement of the driven member 23 for oscillating the agitator 16.

15 The motor 14 is operatively connected to the shaft 81 by mechanism including a grooved pulley 84 which is fixed to the lower end of the motor shaft 75, and another grooved pulley 85 which is freely rotatable on the sleeve member 82. The pulley 85, which is driven by a belt 86 from the pulley 84, is provided with an integrally formed clutch element 87 which cooperates with another clutch element 88 fixed to a collar 89. The clutch element 88 and collar 89 are keyed to the lower end of the vertical shaft 81 and only axially movable on the latter.

20 The collar 89 receives the end of a lever 90 which is pivoted at 91 and arranged to be moved up and down by an operating member 92. The member 92 may be connected by suitable control mechanism (not shown) to a conveniently located manually operable control at the vicinity of the control for connecting and disconnecting the drum 15 to and from the motor 14. When the lever 90 is moved upwardly by the operating member 92, the clutch element 88 engages the element 87, whereby the motor shaft 75 positively drives the shaft 81 through the belt 86 and clutch elements.

25 The manually operable control members for engaging and disengaging the friction clutch members 77 and 78 and clutch elements 88 and 89 may be operated so that the drum 15 and washing element 16 may be independently or simultaneously actuated by the motor 14. Such control members may be mounted on a suitable panel located beneath the table plate 69, and the mechanisms connecting such control members to the operating members 80 and 92 may also be enclosed in one or more tubular members (not shown) which are like the hollow tube 83 and positioned adjacent thereto in the gap between the washing unit 10 and liquid extracting unit 11.

30 By housing the motor 14 in the lower compartment 14 within the casing 42, the motor is effectively shielded and protected from liquid and also the heat developed by the burner 12 when heating of the washing liquid in the receptacle 17 is desired. A suitable opening having a sliding cover (not shown) may be provided in the housing 29 of the washing unit 10 to facilitate igniting the gas issuing from the nozzles of the burner 12.

35 The relatively short distance between the base 9 and the supporting surface upon which the apparatus rests, together with the provision of the flange 57 at the bottom of the base 9 which serves as an apron or skirt, prevents liquid from splashing and coming in contact with the motor 14 and the exposed motion transmitting mechanism beneath the top plate 55 of the base. However, for additional protection a plate 93 may be remov-

ably secured, as by clips (not shown), for example, at the bottom of base 9 beneath the motor 14 and the mechanism operatively connecting the motor and the vertical shaft 81. As clearly seen in Fig. 1, the space beneath the top plate 55 of base 9 by itself is of insufficient height, when the base is being supported on the supporting surface 68, to house the transmission parts beneath the motor 14 and the motor in its entirety in the vertical position illustrated. In the preferred embodiment shown, the space beneath the top plate 55 of base 9 by itself actually is of insufficient height to house the motor 14 in its entirety in the vertical position illustrated.

The central aperture in the collar or ring 61 is of such size that, after the belt 86 is detached from the pulley 84 and the motor 14 is disconnected from the ring at 76, it can be freely withdrawn from the compartment 74 at the underside of the base 9. The friction clutch element 77 is withdrawn with and accompanies the motor while the other element 78 remains in position on the shaft 49. When the table plate 69 is removed after loosening its connections, the casing 42 can be readily removed from the top plate 55 without disturbing the washing unit 10. When control provisions are provided immediately beneath the table plate 69, it may be necessary in such case to disconnect such controls from the table plate 69 to permit removal of the casing 42 from the base 9. When this is done, the motor 14 remains connected to the ring 59.

In view of the foregoing, it will be seen that an improved apparatus has been provided for washing clothes and centrifugally extracting liquid therefrom in adjacent units separately mounted on a common base. The assembly of the component parts is simple and the construction is of such nature that each part is readily accessible and may be interchanged with a similar part while disturbing only a minimum number of other parts of the apparatus.

In addition to providing a simple and economical construction, the different parts are so arranged in relation to one another that maximum protection from splashed liquid is obtained. In the preferred embodiment this relationship of parts involves providing the base 9 having a plate or member which is relatively near to a supporting surface upon which the apparatus is adapted to rest, the base having a skirt or apron to provide a space at its underside which is effectively shielded from liquid which may be splashed. The shell 42 of the liquid extracting unit 11, whose upper end is substantially at the same level as the top of the washing receptacle 17, is of such height that the washing and liquid units 10 and 11 are at a convenient working level.

The shell 42 extends below the bottom of the washing receptacle 17 while the driving motor 14 is disposed beneath the drum 15 and below the bottom of the washing receptacle. The motor 14 is mounted at 76 so that a major portion thereof is housed within the compartment 74 with the shaft 75 extending vertically and in alignment with the drum 15.

The mechanism for transmitting motion from the upper end of shaft 75 is disposed entirely within the compartment 74 while the mechanism for transmitting motion from the lower end of the motor shaft to the washing element 16 is disposed entirely outside the shell 42. This is accomplished by mounting the motor 14 so that the shaft 75 projects downwardly into the horizontally extending space defined by the base 9 and extending downwardly from the top plate 75

55 of the latter. The mechanism for actuating the washing element 16 is independent of the mechanism provided for driving the drum 15 and includes one portion of the space at the underside of the top plate 55 of base 9, which is readily accessible from the underside of the base 9, and another portion which extends upwardly in the gap between the units 10 and 11 from the base 9 to a height above the bottom of the receptacle 17.

The opening in the base 9 at the region of the shell 42 affords access into the motor compartment 74, the connections 76 for mounting the motor being readily accessible at such opening. By simply detaching the belt 86 from the motor pulley 84 and disconnecting the motor from its mounting, the latter can be readily withdrawn from the compartment 74, as previously explained.

20 Although we have shown a single embodiment of our improved apparatus for washing clothes and centrifugally extracting liquid therefrom, we do not desire our invention to be limited to the particular arrangement set forth, and we intend in the claims to cover all modifications which do not depart from the spirit and scope of our invention.

25 What is claimed is:

1. In washing apparatus of the class described having a washing unit including a washing receptacle and a washing element mounted for movement therein and a liquid extracting unit including an upright casing and a drum mounted therein for rotation about a vertical axis to extract liquid centrifugally from clothes, the combination of a base, means for mounting the washing unit and liquid extracting unit on said base alongside each other, said base having an opening affording access into the lower end of the casing, a single electric motor mounted in the lower part of the casing beneath the drum, said motor being vertically disposed and having a driving element rotatable about a vertical axis substantially in alignment with the axis of rotation of the drum, means for supporting said base on a supporting surface, said supporting means 30 providing a space beneath said base, means disposed entirely within the casing for transmitting motion from the upper end of said driving element to the drum to rotate the latter, transmission mechanism disposed entirely outside the casing for transmitting motion from the lower end of said driving element to the washing element, said mechanism including parts in the space beneath said base at the vicinity of the opening in the casing, the space beneath said base by itself being of insufficient height, when said base is being supported on the supporting surface, to house said transmission parts and said motor in its entirety in said vertical position, and said base having provisions including a 35 downwardly depending skirt at the periphery thereof to protect said motor and last-mentioned parts from any liquid splashed at the vicinity of said base.

2. In washing apparatus of the class described 40 having a washing unit including a washing receptacle and a washing element mounted for movement therein and a liquid extracting unit including an upright casing and a drum mounted therein for rotation about a vertical axis to extract liquid centrifugally from clothes, the combination of a base, means for mounting the washing unit and liquid extracting unit on said base alongside each other, said base having an opening affording access into the lower end of the casing, a single electric motor having a driving 45

shaft, means accessible at the opening for mounting said motor vertically with a major portion thereof positioned within the lower part of the casing beneath the drum and the lower end of the vertical driving shaft projecting downwardly beyond the lower end of the casing, said driving shaft being rotatable about a vertical axis substantially in alignment with the axis of rotation of the drum, means for supporting said base on a supporting surface, said supporting means providing a space beneath said base, means disposed entirely within the casing for transmitting motion from the upper end of said driving shaft to the drum to rotate the latter, transmission mechanism disposed entirely outside the casing for transmitting motion from the lower end of said driving shaft to the washing element, said mechanism including parts in the space beneath said base at the vicinity of the opening in the casing, the space beneath said base by itself being of insufficient height, when said base is being supported on the supporting surface, to house said transmission parts and said motor in its entirety in said vertical position, and said base having provisions including a downwardly depending skirt at the periphery thereof to protect said motor and last-mentioned parts from any liquid splashed at the vicinity of said base.

3. Apparatus as set forth in claim 2 in which the parts of said transmission mechanism in the space beneath said base include a pulley on said driving shaft and an endless belt cooperating therewith.

4. In washing apparatus of the class described having a washing unit including a washing receptacle and a washing element mounted for movement therein and a liquid extracting unit including an upright casing and a drum mounted therein for rotation about a vertical axis to extract liquid centrifugally from clothes, the combination of a base, means for mounting the washing unit and liquid extracting unit on said base alongside each other, said base having an opening affording access into the lower end of the casing, a partition intermediate the ends of the casing to subdivide the latter into upper and lower compartments, means including the partition for mounting the drum in the upper compartment for rotation about a vertical axis, a single electric motor having a driving element, mounting means accessible at the opening for removably supporting said motor within the casing in the lower compartment thereof to position said driving element for rotation about a vertical axis substantially in alignment with the axis of rotation of the drum, means for supporting said base on a supporting surface, said supporting means providing a space beneath said base, first mechanism disposed entirely within the casing for transmitting motion from said driving element to the drum to rotate the latter, second mechanism disposed entirely outside the casing for transmitting motion from said driving element to the washing element, said second mechanism including parts in the space beneath said base at the vicinity of the opening in the casing, such parts including a pulley on said driving element and an endless belt cooperating therewith, the space beneath said base by itself being of insufficient height, when said base is being supported on the supporting surface, to house said transmission parts and said motor in its entirety in said vertical position, and said base having provisions including a downwardly depending skirt at the periphery thereof to pro-

5 10 15 20 25 30 35 40 45 50 55 60 65 70 75 75

tect said motor and last-mentioned parts from any liquid splashed at the vicinity of said base, said first mechanism being so constructed and arranged that, after said endless belt is removed from said pulley and said mounting means is disconnected, said motor can then be freely withdrawn from the lower compartment.

5. In apparatus having a liquid extracting unit including an upright casing and a rotatable drum for centrifugally extracting liquid from clothes, such unit being mounted on a base, the combination of such a base having an opening affording access into the lower part of the casing, the casing having a partition intermediate the ends thereof to subdivide the latter into upper and lower compartments, means including said partition for journaling the drum for rotation in the upper compartment about a vertical axis, said last-mentioned journaling means supporting the entire dead-weight load of the drum and clothes therein from which liquid is adapted to be centrifugally extracted, an electric motor having a shaft, readily accessible mounting means on said casing adjacent said opening for removably supporting said motor in the lower compartment to position the shaft vertically therein for rotation about a vertical axis substantially in alignment with the stub shaft of said drum, means for supporting said base on a supporting surface, said supporting means providing a space beneath said base, connecting means operable to connect said motor shaft and the drum, said connecting means including a clutch having cooperating elements associated with the drum and motor shaft, respectively, the space beneath said base by itself being of insufficient height, when said base is being supported on the supporting surface, to house said motor in its entirety in said vertical position, said elements being freely separable when said motor is withdrawn from the lower compartment, and said element associated with said motor accompanying the latter upon its removal from said casing.

TORD ERIK DANIEL BILDE.
